UNITED STATES PATENT OFFICE.

ANNA K. MAY, OF PHILADELPHIA, PENNSYLVANIA.

DESIGN FOR CARPET.

SPECIFICATION forming part of Design No. 26,055, dated September 15, 1896.

Application filed July 30, 1896. Serial No. 601,110. Term of patent 3½ years.

To all whom it may concern:

Be it known that I, ANNA K. MAY, a citizen of the United States, residing at Philadelphia, in the county of Philadelphia and State of Pennsylvania, have invented and produced 5 a new and original Design for a Carpet or other Fabric, of which the following is a specification and description.

The design of my invention may be applied 10 to or wrought in Brussels, velvet, Wilton, in-grain, or other carpeting in such colors and combinations of colors as may be desired; and I do declare that the various shapes and figures 15 which appear on the accompanying drawing are an expression of my design and enable it to be fully understood.

The leading feature of my design may be 20 said to be daffodils and daffodil and crocus foliage.

In the drawing, a is the body, b the border, and a b the complete carpet.

c are daffodils more or less conventionalized.

d is crocus foliage.

e is daffodil foliage, and f are crocus flowers.

What I claim as my invention, and desire to secure by Letters Patent, is—

1. In a design for a carpet, the body a, substantially as shown.

2. In a design for a carpet, the border b, substantially as shown.

3. The design for a carpet consisting of the body a, and border b, substantially as shown.

In testimony whereof I have hereunto signed my name in the presence of two witnesses.

ANNA K. MAY.
